CURTAIN STRETCHER

Edward M. Scott, Pasadena, Calif.

Application July 9, 1948, Serial No. 37,902

5 Claims. (Cl. 45—24)

1

The invention relates to a curtain stretcher, and more particularly to a foldable, knockdown and adjustable curtain stretcher or the like.

The primary object of the invention is the provision of a stretcher of this character, wherein in the stretching bars are sectional, these being hinged together, both at the longitudinal and transverse courses thereof, so that such bars are susceptible of folding while assembled in frame formation, to enable the stretcher to be contracted or reduced in size when not in use to occupy the least possible space for storage, and under the assembly the stretcher is susceptible of being knocked down.

Another object of the invention is the provision of a stretcher of this character, wherein in addition to the folding feature, the stretching bars when unfolded are interconnected in frame formation, in a manner to permit of outward pulling thereon to increase the width and length of the frame formation adapting it correspondingly to the size of the work to be held and stretched, or such bars can be moved relative to each other, for decreasing the size of the frame formation, as the occasion may require.

A further object of the invention is the provision of a stretcher of this character, wherein the stretching bars after adjustment relative to each other, they can be latched in determined position, the bars being provided with scale markings thereon, for identifying distances thereof from center of the frame formation, while associated with the latter are supporting legs for holding it while in use in an upright position.

A still further object of the invention is the provision of a stretcher of this character, wherein it is made from metal and is devoid of clamps, or the like, thus its metal make-up renders it weather-proof and being clampless makes it quickly adjustable.

A still further object of the invention is the provision of a stretcher of this character, which is simple in construction, thoroughly reliable and efficient in operation, strong, durable, readily and easily folded and unfolded, quick of adjustment, possessed of few parts, novel and unique in assembly of its parts, and inexpensive to manufacture.

With these and other objects in view the invention consists in the features of construction, combination and arrangement of parts as will be hereinafter more fully described, illustrated in the accompanying drawings, which disclose the

2

preferred embodiment of the invention, and pointed out in the claims hereunto appended.

In the accompany drawings:

5 Figure 1 is a perspective view of the curtain stretcher constructed in accordance with the invention, it being set-up for use.

Figure 2 is an enlarged fragmentary plan view showing one corner assembly of the frame formation.

10 Figure 3 is a detail enlarged plan view of one corner runner and latch for the stretcher frame.

Figure 4 is a sectional view taken approximately on the line 4—4 of Figure 3 looking in the direction of the arrows.

15 Figure 5 is a sectional view taken on the line 5—5 of Figure 3 looking in the direction of the arrows.

Figure 6 is a sectional view taken on the line 6—6 of Figure 4, looking in the direction of the 20 arrows.

Figure 7 is a sectional view taken on the line 7—7 of Figure 6, looking in the direction of the arrows.

Figure 8 is a side elevation of one of the 25 supporting legs for the stretcher, only a portion of the latter being fragmentarily and sectionally disclosed therein.

Figure 9 is a fragmentary plan view of one of the stretching bars, showing by dotted lines the 30 hinge joint and by full lines the covering sleeve for the joint.

Figure 10 is a sectional view taken on the line 10—10 of Figure 9, looking in the direction of the arrows.

35 Similar reference characters indicate corresponding parts throughout the several views in the drawings.

Referring to the drawings, in detail, A designates generally the curtain stretcher or the like in its entirety, while B denotes generally the supporting legs therefor, when it is in a set-up condition for use.

The stretcher A, comprises longitudinal side and transverse end bars 10 and 11, respectively, each being preferably made from metal, tubular in form, and flat faced in cross-section, so that said bars are hollow in kind, although such bars may be made solid and of any other suitable material, as may be desired. Such bars 10 and 11 are composed of several sections of any required length, each section being identified generally at 12, and is linearly straight throughout its length.

The sections 12 of the respective bars 10 and 11 are swingingly connected together by suitable 55 hinges 13, so that such sections may be folded

and unfolded. Slidably fitted onto the bars 10 and 11 are runner clips 14, each adapted to be disposed over the pintle of the hinge 13 to hold the sections 12 against folding when these are in unfolded condition, and by sliding the said clips 14 away from the hinge 13 the sections may be folded, as should be obvious from Figures 2, 9 and 10 of the drawings.

Located at determined areas on the bars 10 and 11, are corner brackets, in the form of runners, each including sleeve-like superposed yokes 15 and 16, respectively, which at their inner flat faced surfaces are joined together by separable fasteners, including the male studs 17 and female cleats 18, as clearly disclosed in Figures 4, 5, 6 and 7, of the drawings, so that the yokes 15 and 16 can be detached from each other to enable the frame of the stretcher to be knocked down, when desired.

The yokes 15 and 16 are slidably accommodated on the bars 10 and 11, companions thereto, so that with their use a stretcher frame is created, the bars 10 being parallel with each other in a longitudinal direction and likewise the bars 11 parallel with each other in a transverse direction in the frame formation, with the bars 10 and 11 crossing one another. Such bars 10 and 11 can be adjusted toward or away from one another to increase or decrease the size of the frame when set-up for service, accordingly to the requirements of the work to be handled thereby.

The brackets involving the yokes 15 and 16, each has the latter disposed to receive the bars 10 and 11 at a point where one bar 10 crosses a bar 11, as clearly shown in Figures 1, 2, 3 and 5 of the drawings. On the inner edges longitudinally of the bars 10 and 11 are spaced tackings, such as billed hooks 19, which may be struck from the sections 12, or otherwise created, so that a curtain or the like (not shown) can be attached to the frame throughout the sides and end thereof, for the stretching of such curtain or the like. The yokes 16 and 15 are so constructed to not interfere with the hooks 19 under the sliding adjustment of the corner brackets, when required to increase or decrease the size of the stretching frame.

The sections 12 of the bars 10 and 11 are scale marked at 20, in reverse directions to the medial of such bars to indicate the distanced relationship thereof to the center of the frame when adjusted, and thus visibly identifying accuracy in trueness of the frame contour.

On the yokes 15 and 16 at their exposed sides, each carries a pivotally mounted latching lever 21, the pivot for the same being denoted at 22, and this lever has a biased locking jaw or the like 23, which under the tension of a spring 24 connected to the lever engages in a keeper area 25, it being provided in the outermost edge face of each of the bars 10 and 11, as best seen in Figures 4 and 5 of the drawings, and in this manner the corner brackets are held latched to the said bars in adjusted positions. Each lever 21, preferably, is of the shape shown in Figure 3 of the drawings, and its heel end 26 forming a finger trigger, so that the jaw 23 can be released by hand against the resistance of the spring 24, which urges said jaw or the like to a latching position. Each yoke 15 and 16 has a guard extension 25' for the trigger end 26 of the lever 21, so that injury to an operator is avoided by contact of the hand with the tackings before described.

On the side bars 10, uniformly spaced from one end of the frame, at its under side, are socket

members, each identified at 27, for detachably accommodating therein the hooking terminal 28 of a foldable prop or leg 29, it being provided with a break-joint 30, for folding and unfolding of said prop or leg. A sliding sleeve 31 is provided on the prop or leg 29 and when covering the joint 30 it prevents folding of the said leg or prop. The props or legs 29 are used with the frame of the stretcher to hold it in position to have one end portion elevated, while in use, as is clearly shown in Figure 1 of the drawings.

The legs or props 29 have associated with each and the frame, a brace 32, as shown in applied position in Figure 1 of the drawings for a purpose as common to the use of such braces.

The stretcher frame when unfolded for service, the corner brackets on unlatching permits the adjustment of the frame involving the bars 10 and 11 in accordance with the size of the work attached to the tackings, the adjustments being had by pushing or pulling the bars, and when arriving at the required size of the frame for the stretching of the work, the latches lock the corner brackets and bars in fixed relation to one another, whence a stretching operation takes place on the work.

It should be apparent that the frame when the sections of the bars 10 and 11 have been folded on themselves, can be brought to a compact and retracted condition, on removal of the curtain or the like, after stretching thereof so that the stretcher when not in use can be conveniently handled and stored in the least possible space with ease and dispatch, the legs or props being also foldable for this purpose.

The curtain or the like is applied and removed in the usual manner common to stretchers of the framing type, so a detail explanation of same is omitted for the sake of brevity. Of course, it is understood that the props of legs can be folded with the frame of the stretcher, as provision is made for so doing. It should be obvious that the frame is entirely free of clamps or the equivalent thereof, for the adjustment of the stretcher or for permitting folding thereof.

What is claimed is:

1. A curtain stretcher, comprising a pair of spaced and parallel side bars, a pair of spaced and parallel end bars, all of said bars being formed of metal tubing, brackets connecting said bars together with said end bars at right angles to said side bars, said bars being slidable in said brackets to adjust the size of said stretcher, there being four of said brackets, said brackets each comprising a pair of bar-receiving yokes, each yoke being formed with a channel slidably receiving a bar therein, and means readily detachably connecting said yokes together with said channels extending at right angles to each other.

2. A curtain stretcher, comprising a pair of spaced and parallel side bars, a pair of spaced and parallel end bars, all of said bars being formed of metal tubing, brackets connecting said bars together with said end bars at right angles to said side bars, said bars being slidable in said brackets to adjust the size of said stretcher, there being four of said brackets, said brackets each comprising a pair of bar-receiving yokes, each yoke being formed with a channel slidably receiving a bar therein, means readily detachably connecting said yokes together with said channels extending at right angles to each other, and a pair of spring loaded latches carried by each bracket, each latch normally engaging a bar to lock the same in adjusted relation to said bracket.

3. A curtain stretcher, comprising a pair of spaced and parallel side bars, a pair of spaced and parallel end bars, all of said bars being formed of metal tubing, brackets connecting said bars together with said end bars at right angles to said side bars, said bars being slidable in said brackets to adjust the size of said stretcher, there being four of said brackets, said brackets each comprising a pair of bar-receiving yokes, each yoke being formed with a channel slidably receiving a bar therein, and stud and cleat means readily detachably connecting said yokes together with said channels extending at right angles to each other.

4. A curtain stretcher comprising a pair of spaced and parallel side bars, a pair of spaced and parallel end bars, all of said bars being hollow, brackets connecting said bars together with said end bars at right angles to said side bars, said bars being slidable in said brackets to adjust the size of said stretcher, said brackets each comprising a pair of bar-receiving yokes, each yoke being formed with the channel slidably receiving a bar therein, and means readily detachably connecting said yokes together with said channels extending at right angles to each other.

5. A curtain stretcher comprising a pair of spaced and parallel side bars, a pair of spaced and

parallel end bars, all of said bars being hollow, brackets connecting said bars together with said end bars at right angles to said side bars, said bars being slidable in said brackets to adjust the size of said stretcher, each of said brackets comprising a pair of bar-receiving yokes, each yoke being formed with a channel slidably receiving a bar therein, means readily detachably connecting said yokes together with said channels extending at right angles to each other, and a pair of latches carried by each bracket, each latch normally engaging a bar to lock the same in adjusted relation to said bracket.
